UNITED STATES PATENT OFFICE.

FRIEDRICH MAUSSNER, OF NÜREMBERG, ASSIGNOR TO FREDERIC OCHS, OF FUERTH, GERMANY.

SANITARY MATTRESS.

SPECIFICATION forming part of Letters Patent No. 468,353, dated February 9, 1892.

Application filed October 26, 1891. Serial No. 409,812. (No model.)

To all whom it may concern:

Be it known that I, FRIEDRICH MAUSSNER, a subject of the King of Bavaria, in the German Empire, and a resident of the city of 5 Nüremberg, in the Kingdom of Bavaria, Germany, have invented certain new and useful Improvements in Sanitary Mattresses, of which the following is a specification.

My invention relates to sanitary mattresses 10 for children and sick persons who are not able to hold the urine while sleeping and are in consequence thereof liable to catch severe colds while resting on a wet sheet of rubber or blanket with parts of their body exposed 15 during cold nights.

My invention consists in a combination of parts by means of which the moisture is removed from the surface nearest to the body by being absorbed by a porous sheet at the 20 bottom of the mattress, the whole being inclosed in a cup-shaped water-tight casing, from which it can be easily removed.

In the accompanying drawings, Figure 1 is a section through the sanitary mattress. Fig. 25.2 is a plan view of the same.

Similar letters refer to similar parts throughout the several views.

For the main part of the mattress I select a bolster or thick mat *m*, made of horse-hair 30 or similar fibrous material loosely interwoven by hand or machine, at the bottom of which I place a blanket *c*, of felt or similar moisture-absorbing material, and inclose both in a quilt *b*, which is made of thin and loosely- 35 woven textile fabric and cut in a peculiar disk-like shape corresponding to the shape of the bolster, covering its entire upper surface, and after extending downward, covering the sides of both the bolster *m* and the 40 felt blanket *c*, is drawn in by bending-strips *b'*, overlapping the four sides of the mat *m* and felt blanket *c*, till they touch the bottom 45 of the blanket *c*, and then connect them at the overlapping four corners by sewing or cementing them together, thus holding the mat *m* and blanket *c* together, yet allowing their easy removal through the open space left through the rim *b'*. This combination is inserted into a casing of rubber cloth *a* or 50 similar material formed in a similar manner as the quilt *b*, with an overlapping rim *a'*, in such a manner that rim *b'* is placed at the opposite side of the mattress from the rim *a'*, or the open side of the quilt *b* is turned

downward, while the open side of the rubber-cloth casing *a* is turned upward, as shown in Figs. 1 and 2.

In applying my invention the mattress is placed into a bed in the manner described, with the open side of the rubber casing 60 turned upward. Thin bed-clothing, if any, is spread thereover and is thus made ready for use. The urine emitted will easily pass through the thin quilt *b* and mat *m* and will be gradually absorbed by the underlying 65 porous strip *c*, and will be retained therein, the rubber-cloth casing preventing its spreading beyond and wetting the slats and the floor, thus keeping the child resting upon the mattress almost dry when compared with the 70 common custom, where the directly underlying sheet of rubber cloth prevents the escape-ment of the urine and will keep the child thus affected frequently wet, thus breeding disease. It is evident that the casing *b* could 75 be omitted and the felt strip *c* placed sepa- rate into the rubber casing *a* and casing *b* in- close the mat *m* alone, if desired.

All the parts of these sanitary mattresses can be easily separated, cleaned, or dried and 80 readily put together again.

This mattress is especially adapted to use in all cases of surgical or medical operations where liquids of any kind are liable to be spilt, as in bathing or washing the body or 85 limbs or where there is danger of hemorrhage at night, &c.

Having thus described my invention, what I claim, and desire to secure by Letters Patent, is—

1. The combination, in a sanitary mattress, of the mat *m* with the porous sheet *c*, the open-fabric casing *b*, having the rim *b'*, and the impervious casing *a*, having the rim *a'*, as and for the purposes herein shown and de- 95 scribed.

2. In a sanitary mattress, the combination of the mat *m* with the porous sheet *c* and the impervious casing *a*, having the rim *a'*, as and for the purposes herein shown and set 100 forth.

Signed at Fuerth, in the Kingdom of Bavaria and Empire of Germany, this 7th day of October, A. D. 1891.

FRIEDRICH MAUSSNER.
